CLAIM

The ornamental design for a humidity, light and fan control PIR occupancy sensor, as shown and described.

DESCRIPTION

FIG. 1 is a front perspective view of a first embodiment of a humidity, light and fan control PIR occupancy sensor; FIG. 2 is a rear perspective view of the sensor of FIG. 1. FIG. 3 is a front plan view of the sensor of FIG. 1; FIG. 4 is a left side plan view of the sensor of FIG. 1; FIG. 5 is a right side plan view of the sensor of FIG. 1; FIG. 6 is a top view of the sensor of FIG. 1; FIG. 7 is bottom view of the sensor of FIG. 1; FIG. 8 is a back plan view of the sensor of FIG. 1; FIG. 9 is a front perspective view of a second embodiment of a humidity, light and fan control PIR occupancy sensor; FIG. 10 is a rear perspective view of the sensor of FIG. 9. FIG. 11 is a front plan view of the sensor of FIG. 9; FIG. 12 is a left side plan view of sensor of FIG. 9; FIG. 13 is a right side plan view of the sensor of FIG. 9; FIG. 14 is a top view of the sensor of FIG. 9; FIG. 15 is bottom view of the sensor of FIG. 9; and, FIG. 16 is a back plan view of the sensor of FIG. 9. The broken lines are for illustrative purposes only and form no part of the claimed design.
